UNITED STATES PATENT OFFICE.

ALPHONSE BERNARD-SCHMOLLE, OF LONDON, ENGLAND.

SIPHON.

1,056,394.

Specification of Letters Patent.

Patented Mar. 18, 1913.

Application filed May 21, 1910. Serial No. 562,593.

To all whom it may concern:

Be it known that I, ALPHONSE BERNARD-SCHMOLLE, a citizen of the United States, residing at London, England, have invented 5 certain new and useful Improvements in Siphons, of which the following is a specification, reference being had to the accompanying drawings.

This invention relates to improvements in 10 siphons and particularly to improvements in siphons adapted for use with bottles, flasks and like containers or receptacles and to fit in the neck thereof; and an object of this invention is to provide a siphon of the type 15 just mentioned which will prove simple in construction, relatively cheap in manufacture and highly efficient in use.

Another object of this invention is to provide a siphon of the character described with 20 means for charging the bottle with an expandible fluid, such as a suitable gas.

A third object of this invention is to provide a siphon of the class referred to with a blow-off device which will prevent the bottle 25 from becoming overcharged with the gas.

A further object of this invention is to provide a siphon with an efficient gas-check or fermeture for sealing the mouth of the receptacle.

30 In the drawings illustrating the principle of this invention and the best mode now known to me of applying that principle, Figure 1 is an elevation, partly in section, of a bottle provided with my new siphon; 35 Fig. 2 is a vertical central section through the gas reservoir and the means controlling the outlet thereof; and Fig. 3 is a detail in section showing the connection between the gas-reservoir and the interior of the bottle 40 which contains the liquid to be dispensed.

The interior wall of the neck or mouth *a* of the bottle *b* is formed with a circular groove *c* in which is fitted a rubber gasket-ring *d* which is carried by the siphon-pipe *e* 45 and which rests upon the washer-nut *f* formed thereon. The lock-nut *f'* serves to hold the latter in its adjusted position. The siphon-pipe *e* passes through the bore of a tubular stopper *g* the inner end of which 50 rests upon the top of the gasket-ring *d* and the outer end of which is formed with a flanged head *g'* which is adapted to rest on the top of the bottle *b* and to cover the mouth *a* thereof. The part *e'* of the siphon-pipe *e* 55 which projects just above the head *g'* of the stopper *g* is screw-threaded and on it is

mounted a wing-nut *h* by turning which in the proper direction pressure may be brought to bear upon the stopper *g* and by the latter transmitted to the rubber gasket-ring *d*, 60 whereby the latter is compressed between the inner end of the stopper and the washer-nut *f* and is forced tightly into and against the wall of the circular groove *c* to form a gas-tight joint at this point. Hence, the 65 gasket-ring *d* serves as a gas-check or fermeture to prevent the escape of gas from the bottle by way of the mouth thereof.

The upper end of the glass siphon-tube *i* is provided with a metal sleeve or collar *j* the 70 top of which is cupped and interiorly-threaded and is thereby adapted to be screwed upon the threaded portion *e''* of the metal siphon-pipe *e* which lies just below the washer-nut *f*. The lower end of the glass 75 siphon-tube *i* extends, as usual, almost to the bottom of the bottle *b*.

Above the threaded portion *e'* the metal siphon-pipe *e* is formed with a nozzle or spout *k* and is provided with a valve or tap 80 *m* which may, of course, be of any suitable type and which forms in itself no part of this invention. On the valve-casing *m'* of the valve *m* and integral therewith is formed a hollow support or post *n* having a nipple *o* 85 into which is screwed the threaded end of the outlet-pipe *p* which leads from the bulb-shaped gas-reservoir *q*. The latter is adapted and designed to hold compressed carbonic acid gas or other suitable expandible fluid. 90 On its side opposite from the nipple *o* the hollow post *n* carries a cup *r* in which is mounted a diaphragm *s* which is adapted to bear against the projecting end of a valve *t* mounted in the outlet pipe or passage *p*. 95 Into the cup *r* is screwed a perforated screw-cap *u* through which extends a plunger *v* the inner end *v'* of which is adapted to press against the diaphragm *s* for the purpose of opening the valve *t*. The chamber *n'* in the 100 hollow post *n* is connected by a nipple *n''* and a piece of rubber tubing *w* with a nipple *x* which communicates with the upper end of the passage *e''* formed in the siphon-pipe *e* (Fig. 3); that is, the connection between 105 the nipples *n''*, *x*, lies outside the valve-casing *m'* and consists of a bit of rubber tubing *w*. In case too much gas is inadvertently allowed to flow from the gas-reservoir *q* or in case the valve *t* should leak, excessive gas 110 pressure thus produced will be relieved by the gas leaking past the ends of the rubber

tubing w , or by its blowing the latter off the nipples. Hence, the rubber tubing serves as a sort of safety valve or blow-off device in case the pressure of the gas in the flask b rises too high. The outlet for the gas flowing from the gas-reservoir q into the flask b through the siphon-pipe e is the hole y which is in the threaded part e'' of the latter and which forms the inner or lower end 10 of the passage e^x (Fig. 3).

It will be observed that the structure hereinbefore described is very compact and simple in its construction. Since the passage e^x for the gas lies within the wall of the siphon-pipe or siphon-tube e , the exterior 15 of the wall may be threaded and the bottle-sealing devices d , g , h may be mounted directly on the wall. By the provision of the passage n'' , w , x the gas-reservoir outlet n' (Fig. 3) is connected with the inlet end of 20 this passage e^x ; and since this passage lies outside of the siphon-tube and leads the gas thereby around the outlet k for the discharge of the beverage, it is practicable to 25 make this conduit include a blow-off safety device, such as the readily detachable rubber tubing w .

I claim:

1. In an apparatus of the character described, the combination of a valve-controlled gas-reservoir; a siphon-tube which carries said gas-reservoir and which is provided with a valve-controlled outlet for the beverage, the bore of said tube being arranged to communicate with said outlet and the wall of said bore being provided below 35 said outlet with a passage for the gas; and a conduit which leads the gas around said outlet and connects the outlet from said gas-reservoir with said passage and which includes a safety blow-off member.

2. In an apparatus of the character described, the combination of a valve-controlled gas-reservoir; a siphon-tube which carries said gas-reservoir and which is provided with a valve-controlled outlet for the beverage, the bore of said tube being arranged to communicate with said outlet and the wall of said bore being provided below 45 said outlet with a passage for the gas; a conduit which leads the gas around said outlet and connects the outlet from said gas-reservoir with said passage and which includes a safety blow-off member; and bot-

tle-sealing means mounted on said wall 55 above the outlet end of said passage.

3. In an apparatus of the character described, the combination of a siphon-tube having a valve-controlled outlet with which the bore of said tube is arranged to communicate for the discharge of the beverage, the wall of said bore being provided with a passage for gas; a valve-controlled gas-reservoir; a conduit which connects the outlet of the latter with the inlet of said passage and which is provided with a safety device for preventing too high back pressure of the gas; and bottle-sealing means mounted on said wall above the outlet of 60 said passage.

4. In an apparatus of the character described, the combination of a siphon-tube having a valve-controlled outlet with which the bore of said tube is arranged to communicate for the discharge of the beverage, 75 the wall of said bore being provided with a passage for gas; a valve-controlled gas-reservoir, a safety blow-off device which connects the latter with the inlet end of said passage; and bottle-sealing means mounted on 80 said wall above the outlet of said passage.

5. A siphon having a siphon-tube which is provided with a valve-controlled outlet for the beverage, said tube being formed above said outlet with a passage for gas 85 and the bore of said tube below said outlet being arranged to communicate with said outlet; the wall of said bore being provided below said outlet with a passage for gas; a blow-off safety-device which lies outside of said tube and which connects said 90 passages for gas; means for forcing gas through said passages and device; the latter conducting the gas from said means around said outlet into the passage formed 95 in the wall of the bore of said tube below said outlet and said wall being exteriorly threaded; and bottle-sealing means mounted on said exteriorly-threaded wall.

In witness whereof I hereunto set my hand at London, England this eighteenth day of April, 1910, in the presence of the undersigned witnesses.

ALPHONSE BERNARD-SCHMOLLE.
